CLAIM

The ornamental design for an insert for a painting container, as shown and described.

DESCRIPTION

FIG. 1 shows a perspective view of an insert for a painting container.

FIG. 2 shows a top view of the insert in FIG. 1.

FIG. 3 shows a bottom view of the insert in FIG. 1.

FIG. 4 shows a front view of the insert in FIG. 1.

FIG. 5 shows a rear view of the insert in FIG. 1.

FIG. 6 shows a left-side view of the insert in FIG. 1; and, FIG. 7 shows a right-side view of the insert in FIG. 1.

The portions of the design shown in broken or dotted lines are for illustrative purposes only and form no part of the claimed design.

1 Claim, 7 Drawing Sheets
